STOP MECHANISM FOR REELING MACHINES

Dirk Slikker, Enka, N. C., assignor to American Enka Corporation, Enka, N. C., a corporation of Delaware

Application March 25, 1937, Serial No. 133,037

5 Claims. (Cl. 242—49)

This invention relates to machines for reeling or winding continuous strands or webs of material, such for example as thread or yarn, and more particularly aims to provide a mechanism for automatically stopping the machine after a predetermined length of material has been wound thereon.

An important object of the invention is to provide in combination with reeling or winding machines of the above character an automatic stop mechanism comprising a rotary member, such as a disk, operatively connected either directly or indirectly to the reel or winding drum so as to be driven in synchronism therewith and having means associated therewith adapted after a predetermined period of angular displacement to effect the actuation of a control member for arresting rotation of the reel or winding drum. According to the preferred form of my invention the stop mechanism comprises a spring-biased shift bar normally retained in inoperative position by the disk and means upon the disk to release the shift bar for actuating the control member.

Another object of my invention is to provide an automatic stop mechanism, which I term an auxiliary stop mechanism, adapted to be incorporated in a reeling or winding machine of the above character for controlling the winding of comparatively short lengths of material and adapted to be employed in conjunction with a second, or primary, stop mechanism, said auxiliary stop mechanism being so constructed and arranged as to be readily rendered ineffective by a simple manual operation when the machine is to be operated under the control of the primary stop mechanism.

The invention has for a further object to provide an automatic stop mechanism of the above character which is comparatively simple in construction and positive and reliable in operation, an advantageous feature of the stop mechanism residing in the provision of a scale upon the disk and a stationary index member cooperating therewith to afford means for accurately gauging the length of the material to be wound.

Other objects and advantages will be apparent from the following detailed description of a preferred embodiment of the invention, reference being had to the accompanying drawings in which:

Figure 1 is a perspective view of one end of a machine for reeling threads into skeins, with parts broken away for clearness;

Figure 2 is a detail view in side elevation of the

mechanism for transmitting motion from the driven shaft to the actuator disk of the primary and auxiliary stop mechanisms;

Figure 3 is a detail view in side elevation of the primary and auxiliary stop mechanisms; and

Figure 4 is a plan view of the stop mechanism shown in Fig. 3.

Now in referring to the drawings in detail, Fig. 1 illustrates one end of a machine for unwinding artificial silk threads from bobbins and reeling them into skeins. The reeling machine, aside from the stop mechanisms later to be described, is generally of a well-known construction comprising a machine frame 1, a drive shaft 2 extending longitudinally of the frame and suitably journaled in bearings 3 (only one being shown) at opposite ends of the frame, and a driven shaft 4 located above and extending parallel to the drive shaft. The driven shaft 4 in reeling machines of this general character is usually composed of two longitudinal sections rotatable as a unit, upon one of which sections is fixedly mounted a pulley 6 adapted to be frictionally driven from a pulley 5 fastened upon the drive shaft 2, and having secured upon the other of said sections a reel 7. The longitudinal sections of shaft 4 are detachably coupled by conventional means not shown to permit the ready removal of the reel from the machine to allow stripping the skeins of thread therefrom. The threads 8 are wound onto the reel from bobbins 9 arranged upon spindles 10 projecting upwardly from a platform 11 extending along a side of the machine frame. The threads pass upwardly from the bobbins onto the reel through the eyes of horizontal guide pins 12, thence between the longitudinal bars 13 extending along the side of the machine frame and through the thread guides or detectors 14.

The driven reel shaft 4 is rotatably supported within bearings located at opposite ends of the machine. A bracket carrying the bearing for the forward end of the shaft is indicated at 15 and comprises a pair of parallel arms 15a and 15b fastened at one end upon a horizontal rock shaft 16, suitably journaled for rotation in the machine frame, and having at their opposite outer ends bearings 16a for the driven shaft 4. Extending diagonally downward from the outer free end of the arm 15a is a leg 17 terminating in a depending foot 17a. The foot 17a engages a toe 19 upon the end of an angled control lever 20 pivoted upon a pin 21 to the machine frame adjacent its toe end. The control lever has a horizontal handle 22 which projects laterally be-

yond one side of the machine frame. A coil spring 23 extending between the leg 17 of the bracket 15 and the machine frame maintains the leg in engagement with the toe 19; however the handle 22 of the control lever is so weighted as to overcome the opposition of the spring and rock the bracket 15 upwardly, to lift the pulley 6 out of engagement with drive pulley 5 and press it against a stationary brake block 24 suitably positioned upon the machine frame. If desired a strong coil spring (not shown) may be employed, instead of or in addition to the weight of the handle 22, for urging the control lever downwardly. A stop 20a upon the control lever engages an abutment upon the machine frame to limit the downward movement of the control lever.

Along that side of the machine frame from which the threads are delivered to the reel there is provided a reciprocating traverse bar 25 carrying the series of thread guides or detectors 14 through which the threads pass and this traverse bar is actuated by the mechanism shown in Fig. 2 so as to insure the even distribution of the threads upon the reel. As indicated in Fig. 2, a shaft 26 extends crosswise of and is suitably journaled for rotation in the machine frame below driven shaft 4. This shaft is provided at one end with a worm wheel 27 which engages a worm (not shown) on the driven shaft, and upon its other end is fixed a crank 28 to which is pivoted a link 29. The link is in turn connected to the traverse bar, in a manner not shown but which is well understood in the reeling art, so that as the crank slowly rotates, the traverse bar carrying the thread guides moves back and forth to evenly lay the thread down upon the reel.

The reeling machine is provided with an automatic stop mechanism, which I designate the primary stop mechanism, constructed as follows:

Extending crosswise of the machine frame at its end in which are journaled the pulleys 5 and 6, and rotatably supported within spaced bearing members 30 and 31 projecting upwardly from a casting 37 secured to the top of the frame, is a shaft 32. The extended end of reel shaft 4 is positioned below the shaft 32 and at right angles thereto and provided with a worm 33. This worm meshes with a worm wheel 34 secured upon the lower end of a spool 35 rotatable about an upright pintle 36 upon the casting 37. Adjacent its upper end the spool is provided with a worm 38 which meshes with a worm wheel 39 upon the shaft 32.

Worm wheel 39 forms one end of a sleeve 40, freely rotatable upon the shaft 32, which is adapted to be coupled to the shaft 32 by means of a collar 41 adjustable along the shaft and provided with splines 42 receivable within complementary slots in an end face of the sleeve. The collar is adapted to be fastened to the shaft, so as to rotate therewith, by a set screw 43. Thus when the sleeve 40 is coupled to the shaft 32 by the collar 41 the shaft is directly driven from worm 38.

In order to obtain a larger gear reduction to allow the shaft 32 to be driven at a slower speed than when it is directly coupled to the worm 38, a countershaft 44 is located above and parallel to shaft 32. Countershaft 44 is also journaled for rotation in bearing members 30 and 31, so that when the collar 41 is uncoupled from sleeve 40 motion may be transmitted to the countershaft through a spur gear 45 located

upon the sleeve and meshing with a companion spur gear 46 of larger diameter secured upon the countershaft by a set screw 46a. Motion from the countershaft is communicated to shaft 32 either through a pair of companion spur gears 47 and 48 of small and large diameters respectively fixed upon the respective shafts, or, alternately, through a pair of companion spur gears 49 and 50 similarly fixed upon these shafts. It will be understood that the ratios of the pairs of intermeshing gears 47, 48 and 49, 50 are different and suitably chosen to give the proper speed reduction between driven shaft 4 carrying the reel 7 and shaft 32.

The countershaft 44 is adapted to be shifted axially in the bearing members 30 and 31 to move either of the pairs of gears 47, 48 and 49, 50 into or out of mesh; and, when the sleeve 40 is coupled directly to shaft 32, the spur gear 46, is moved out of mesh with its companion gear 45 on sleeve 40 by unloosening the set screw 46a and displacing the gear 46 along shaft 44. To allow shifting of the countershaft lengthwise, there is threaded into bearing member 31 a removable retaining pin 51 so located as to tangentially intersect, as desired, any one of three circumferential grooves 52 formed upon an end of the countershaft.

Shaft 32 is extended through the bearing member 31 and mounted upon the end of this shaft so as to rotate therewith in the direction indicated by the arrow in Fig. 3 is an actuator disk 53. Upon the outwardly disposed face of actuator disk 53 is a tappet 54 and upon its opposite face the disk is provided with an extended cylindrical hub 55 connected by a set screw 56 to shaft 32. Formed upon this hub is a second tappet 57 but angularly offset from tappet 54 by 90 degrees.

Bearing member 31 which supports one end of the shafts 32 and 44 is formed with an arm 58 projecting beyond the end of the machine frame and having a slot 59 formed therein. Adjustable within this slotted arm is a stub shaft 60 (Fig. 4) disposed laterally of the arm and parallel to the shaft 32. The stub shaft is retained in fixed position by means of a clamping nut 60a threaded upon a reduced end of the stub shaft received within and projecting beyond the slot 59. Oscillatable upon the stub shaft is a pair of pawls 61 and 62 which extend downwardly and overlie the end face of the machine frame, these pawls having respectively rearwardly reaching arms 63 and 64 disposed at right angles to the pawls and arranged so as to be engaged by the tappets 54 and 57, respectively. During rotation of the actuator disk the tappets serve to alternately and periodically rock these pawls upon the stub shaft.

The lower ends of the pawls are provided with shoulders 65 and 66, the shoulder 65 on pawl 61 being located at a slightly lower elevation than the shoulder 66 on pawl 62 for a purpose later to be explained. The pawls 61 and 62 are designed to engage the equidistantly-spaced teeth 67 of a vertically disposed rack 68 arranged upon the upper end of a slide block 69 which latter is mounted for vertical travel along an end surface of the machine frame and adjacent one corner thereof in the vicinity of the handle 22 of control lever 20. The slide block is guided in its sliding movement by a pair of bolts 70 passing into the frame through elongated slots 71 formed in the slide block, these bolts being provided with flat heads overlying the side edges 75

of the slots. The shoulders 65 and 66 upon the ends of the pawls 61 and 62 are designed to engage the teeth of the rack under the urge of coil springs 72 extending between the pawls and the machine frame. Since, however, the shoulders upon the two pawls are located at different elevations spaced apart a distance less than a rack tooth 67, only one arm will be effective at any time to engage a tooth of the rack and 10 retain the slide block against downward movement.

A strong coil spring 73 (Fig. 1) anchored at one end to the machine frame and fastened at its other end to a handle member 74 for manually lifting the slide block, serves to pull the 15 slide block downwardly to the maximum extent afforded by the slots 71. At its lower end the slide block is formed with an abutment 75 disposed parallel to the side of the machine frame 20 and having a tapered lower face 75a and an approximately horizontal upper face 75b. The tapered face 75a is adapted near the lowermost position of travel of the slide block to engage the end 77 of a hook 79. This hook constitutes 25 the lower portion of an upright arm 80 intermediately pivoted upon a pin 81 to the side of the machine frame, and is so fashioned as to curve around but amply clear the handle 22 of control lever 20.

30 A step 82, adapted to support the handle 22 in an elevated position with the pulleys 5 and 6 in frictional driving engagement, is suitably formed upon the hook as shown in Fig. 3. The end 77 of the hook is so located with respect 35 to the path of travel of the slide block 69 as to be struck by the abutment 75 during the descent of the slide block and swing so as to disengage the step 82 from the handle 22 and allow the handle to fall by gravity. This results in lifting 40 the pulley 6 out of contact with pulley 5 and into engagement with the brake block 24 to arrest the rotation of the reel.

To facilitate the setting of the stop mechanism according to the length of thread to be wound, there is suitably provided in the side 45 of the machine frame a series of apertures 83 equidistantly spaced apart in staggered relation and adapted to receive a metal peg 84. These 50 apertures correspond in number to the ratchet teeth 67 and are spaced apart a distance equal to the spacing between adjacent ratchet teeth. Thus by introducing the metal peg into an appropriate one of the apertures 83 the slide block 55 may be raised by the handle 74 until the upper edge of abutment 75 strikes the peg, at which time the pawl 62 will engage the tooth of the ratchet corresponding to the aperture occupied by the peg.

60 In addition to the primary stop mechanism just described, I provide an automatically operable auxiliary stop mechanism, as follows:

The upper end of arm 80 which is pivoted upon pin 81 so as to swing about an axis parallel to 65 shaft 32 is extended to an elevation above the axis of said shaft. As shown in Figs. 3 and 4, a horizontal shift bar 86 of laterally-offset or stepped form is pivoted by a pin 87 to a standard 70 88 located upon the top of the machine frame. Upon this shift bar intermediate its length and at the foot of the step or offset is fastened a laterally projecting dog 89. The shift bar 86 is urged, by a coil spring 90, extending 75 between the shift bar and a post 91 upon the top of the machine frame, in a direction such

as to maintain the dog yieldingly in engagement with the periphery of the actuator disk.

The actuator disk is provided at equidistantly spaced intervals about its periphery with notches 92, these notches each being defined by a radially cleft forward or leading edge 92a and an arcuate trailing edge 92b, as shown in Fig. 3. Between these notches upon its periphery the disk is graduated to provide a scale 93 with which a pointer 94, supported within the stationary bearing member 31, cooperates to facilitate the setting of the auxiliary stop mechanism prior to the commencement of the preliminary reeling operation, as will later be explained.

The outer or free end of the shift bar 86 is extended beyond the side of the machine frame upon which the upright arm 80 is pivoted, the shift bar and the upper end of the pivoted arm (shown in dotted lines in Fig. 3) being so relatively located that when a notch upon the disk arrives opposite the dog 89, the latter will snap into the notch under the urge of spring 90 and allow the end of the shift bar to engage and rock the pivoted arm thereby disengaging the 25 handle 22 of control lever 20 from the step 82.

A latch 95 suitably recessed so as to provide a detent 96 is pivoted for vertical swinging movement upon the post 91 in order that it may be swung into engagement with the horizontal shift 30 bar 86 and maintain the latter ineffective.

The operation of the apparatus just described is as follows: In transferring the threads from the bobbins 9 onto the reel it is customary to discard the first 200 or 300 yards of thread representing the outer circumferential windings of each bobbin because such thread is apt to be soiled, damaged or otherwise unsuited for further processing. Accordingly the machine is operated in two stages: First, to preliminarily unwind this comparatively short circumferential portion of thread from the bobbins, at which time the auxiliary stop mechanism is effective; and, second, after the skeins of waste threads 35 reeled during this preliminary run have been 40 stripped from the reel, to reel off the longer lengths of threads during the resumed operation of the machine subject to the control of the primary stop mechanism.

In initiating the preliminary run of the machine, the handle 22 of control lever 20 is elevated onto the step 82 of hook 79. The pivoted shift bar 86, at this time being disengaged by the latch 95, is moved by the relatively strong coil spring 90 so as to yieldingly retain the dog 55 29 against the periphery of the actuator disk 53. Since the actuator disk is operatively connected to and driven in synchronism with the reel shaft 4, the disk for a predetermined number of revolutions of the reel—and hence for the reeling 60 of a prescribed yardage of thread from each bobbin 9—will make one complete revolution. When a peripheral notch 92 upon the actuator disk rides into registry with the dog 89, the latter snaps into the notch, allowing the free end 65 of the shift bar to strike the upper end of the upright pivoted arm 80 and swing the latter to disengage the step 82 from the handle 22. The handle drops by gravity to rock the control lever 20 upon its pivot 21 and thereby move the 70 reel-carrying shaft 4 upwardly to disengage driven pulley 6 from drive pulley 5 and pressing the former pulley against the brake block 24 so as to instantly arrest rotation of the reel.

After the reel has been removed from the ma- 75

chine and the skeins of threads unwound from the bobbins during this preliminary run have been stripped therefrom, the reel is replaced in the machine and the auxiliary stop mechanism 5 is now rendered ineffective by swinging the latch 95 into position to engage the shift bar and hold the dog 89 away from the actuator disk. The handle of the control lever is again lifted onto the step 82 and the slide block 69 raised by the 10 workman, by means of the handle 74, until the abutment 75 strikes the metal peg 84 (which will have been previously positioned in an appropriate aperture 83 in the machine frame according to the length of thread to be reeled) and 15 the pawl 62 engages the tooth of the rack that is correlated with the particular aperture occupied by the metal peg.

During the operation of the machine and as the actuator disk rotates, the pawls 61 and 62 20 will be alternately and intermittently tripped by the tappets 54 and 57 upon the disk to permit the slide block to lower step-by-step under the urge of spring 73. As will be apparent one 25 of the pawls is always in engagement with a rack tooth and a complete revolution of the actuator disk is required in order to release each tooth. Upon release of the final (top) tooth of the rack by the pawls, the slide block will be 30 pulled forcibly downward by the coil spring 73 causing the abutment 75 to strike and swing hook 79 to unseat the handle 22 from step 82. When the handle has been thus disengaged it falls and through the control lever 20 stops the 35 rotation of the reel in the manner before described.

The range of effective operation of the primary 40 stop mechanism (and also of the auxiliary stop mechanism) may be increased by driving the actuator disk 53 through the countershaft 44 as has been previously explained. By uncoupling the collar 41 from sleeve 40 and then displacing the countershaft axially so as to bring either 45 of the pairs of gears 47, 48 or 49, 50 in mesh, a different speed relationship between the reel supporting shaft 4 and the actuator disk, and hence a different reeled yardage for every revolution of the disk, is obtainable.

In setting the actuator disk 53 prior to the commencement of the preliminary run of the 50 machine, the set screw 56 upon the hub of the actuator disk is backed off sufficiently to allow the disk to be freely rotated on the shaft 32. The actuator disk is then angularly adjusted upon this shaft so that the pointer 94 coincides with a selected reading on the scale 93 upon the 55 periphery of the disk. By retightening the set screw the actuator disk is again rigidly connected to the shaft 32. The scale is preferably duplicated between successive peripheral notches upon the actuator disk and so calibrated as to afford a reading in conjunction with the pointer 60 of the yardage which will be wound upon the reel before the next notch of the actuator disk becomes effective to release the shift bar 86 to stop the reel. This scale desirably will be 65 of the composite type so as to provide separate readings correlated with the three different speed reduction gearings through which the actuator disk may be driven from the reel-supporting shaft 4.

70 While the actuator disk in the preferred form of the invention just described is provided with three peripheral notches 92, only one is essential to the operation of the auxiliary stop mechanism. A plurality of notches is desirable, however, in order to facilitate the winding in in-

crements of length less than that represented by a complete revolution of the actuator disk. If, for example, one revolution of the actuator disk corresponds to a winding of 300 yards upon the reel it will be clear that by providing 5 duplicative peripheral notches at three equally spaced intervals upon the disk, the auxiliary stop mechanism will be periodically rendered effective at every wind of 100 yards by the reel. Thus to add in increments of 100 yards to the length 10 of the threads that may be already wound upon the reel, it is only necessary to operate the machine under the control of the auxiliary stop mechanism which will serve to interrupt the rotation of the reel at the conclusion of every hundred yard winding interval. 15

It will be apparent that various changes in structure and design may be made in the apparatus described above without departing from the spirit of my invention. 20

I claim:—

1. The combination with a reeling machine including a frame, a reel journaled for rotation upon the frame, means for rotating the reel and a control lever for rendering the reel rotating 25 means inoperative, of an automatic stop mechanism comprising a rotary disk operatively connected with the reel and rotatable in synchronism therewith, a pivoted shift bar adjacent the disk, spring means urging said shift bar into yielding 30 engagement with the periphery of the disk, an upright arm pivoted to the frame and located in the path of movement of the shift bar said upright arm having a step thereon for latching the control lever in elevated inoperative position, and 35 a notch upon the periphery of the disk to release the shift bar for swinging the upright arm to unseat the control lever and permit said control lever to drop to operative position.

2. An auxiliary stop mechanism for use with 40 reeling machines of the type comprising a frame, a reel journaled for rotation in the frame, means for rotating the reel, a control lever for rendering said reel-rotating means inoperative and a primary stop mechanism for actuating the control lever including a rotary disk rotatable in synchronism with the reel, a slide block, pawls actuated by the rotary disk for imparting step-by-step movement to and the eventual release of the 45 slide block, a pivoted arm normally latching the control lever in operative position and having one of its ends located in the path of the slide block so as to be rocked thereby upon release of the slide block and having its other end extending 50 in the locality of the rotary disk, said auxiliary stop mechanism comprising a shift bar located adjacent the rotary disk, means for yieldingly 55 urging the shift bar into contact with the periphery of the rotary disk clear of the pivoted arm, and a peripheral notch upon the rotary disk for receiving the shift bar, the shift bar being so constructed and arranged that upon entering the notch it engages and rocks the pivoted arm to release the control lever. 60

3. An auxiliary stop mechanism for use with 65 reeling machines of the type comprising a frame, a reel journaled for rotation in the frame, means for rotating the reel, a control lever for rendering said reel-rotating means inoperative and a primary stop mechanism for actuating the control lever, including a rotary disk rotatable in synchronism with the reel, a slide block, pawls actuated by the rotary disk for imparting step-by-step movement to and the eventual release of the 70 75

slide block, a pivoted arm normally latching the control lever in operative position and having one of its ends located in the path of the slide block so as to be rocked thereby upon release of the 5 slide block and having its other end extending in the locality of the rotary disk, said auxiliary stop mechanism comprising a shift bar mounted upon the frame and arranged for pivotal movement into contact with the periphery of the disk and into 10 engagement with the pivoted arm, a spring urging said shift bar into contact with the periphery of the rotary disk clear of the pivoted arm, and a peripheral notch upon the rotary disk for receiving the shift bar, the shift bar being so constructed and arranged that upon entering the 15 notch it engages and rocks the pivoted arm to actuate the control lever.

4. An auxiliary stop mechanism for use with reeling machines of the type comprising a frame, 20 a reel journaled for rotation in the frame, means for rotating the reel including a pair of drive and driven transmission members, a control lever for moving said drive and driven transmission members into and out of engagement, and a primary stop mechanism for actuating the control 25 lever including a rotary disk rotatable in synchronism with the reel, a slide block, pawls actuated by the rotary disk for imparting step-by-step movement to and the eventual release of the 30 slide block, a pivoted arm normally retaining the control lever latched with said drive and driven members in operative engagement, said pivoted arm having one of its ends in the path of the slide

block so as to be rocked thereby upon release of the slide block to unlatch the control lever with consequent separation of the drive and driven members and having its other end extending in the locality of the rotary disk, said auxiliary stop 5 mechanism comprising a shift bar located adjacent the rotary disk, means for yieldingly urging the shift bar into contact with the periphery of the rotary disk out of engagement with the pivoted arm and a peripheral notch upon the rotary 10 disk for receiving the shift bar, the shift bar being so constructed and arranged that upon entering the notch it engages and rocks the pivoted arm to release the control lever.

5. The combination with a reeling machine including a frame, a reel journaled for rotation upon the frame, means for rotating the reel and a control for rendering the reel rotating means inoperative, of an automatic stop mechanism comprising a rotary disk adapted to be driven in synchronism with the reel, a pivoted bar adjacent the rotary disk, a spring urging said shift bar into contact with the periphery of the disk, an arm located in the path of movement of the shift bar adapted to maintain said control in inoperative 25 position, a notch upon the periphery of the rotary disk to release the shift bar to swing the arm for operating said control and an index member co-operating with indicia upon the rotary disk to indicate the length of material to be reeled prior 30 to operation of the control.

DIRK SLIKKER.
